[57] CLAIM

The ornamental design for a piston ring compressor, as shown and described.

DESCRIPTION

FIG. 1 is a top perspective view of a piston ring compressor showing my new design;

FIG. 2 is a top plan view; and

FIG. 3 is a cross-sectional view taken along the line 3—3 in FIG. 1.

“The side and end not shown are like the side and end shown respectively, while the undisclosed bottom is conventional in appearance.”

FIG. 2

FIG. 3
